Attorney

UNITED STATES PATENT OFFICE.

STEPHEN BALLARD, OF WINCHESTER, INDIANA.

CIDER-PRESS.

SPECIFICATION forming part of Letters Patent No. 311,713, dated February 3, 1885.

Application filed October 7, 1884. (No model.)

To all whom it may concern:

Be it known that I, STEPHEN BALLARD, a citizen of the United States of America, residing at Winchester, in the county of Randolph and State of Indiana, have invented certain new and useful Improvements in Cider-Presses; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to certain new and useful improvements in cider-presses; and it consists more especially in the construction and combination of the parts, as will be hereinafter set forth, and pointed out in the claims.

In the accompanying drawings, which illustrate my invention, Figure 1 is a perspective view. Fig. 2 is a sectional view taken on the line *x x* of Fig. 1. Fig. 3 is a sectional view taken on the line *y y* of Fig. 2, and Fig. 4 is also a sectional view taken on the line *z z* of Fig. 3.

A A' represent the upper and lower portions of a frame, between which upon vertical shafts are secured pressing-rollers B B. The upper and lower frames are thoroughly braced to each other by vertical bars *b*. The lower portion of the frame A' is provided at its edge with an upwardly-projecting flange, *a*, and an exit-spout, *a'*, through which will pass the juice pressed from the fruit. The upper surface of the lower frame, A', inclines toward the spout *a'*. Between the upper and lower frames, A A', in front of the crushing or pressing rollers B B, to the front standards, *b b*, are secured sheet-metal plates C C, the ends of which are curved so as to conform to the configuration of the rollers. To the lower portion of these plates is secured a trough or spout, C', which lies within a recess formed in the upwardly-projecting rim *a*, and through this trough passes the pomace. It will be apparent that during the pressing operation the rollers revolve from each other at the point where the plates C C bear, thus permitting said plates to cleanly and thoroughly remove

the pomace from the said rollers, thereby permitting the former to pass out through the trough. The rollers B may be corrugated or have other approved outward configuration, and these rollers are provided with vertical shafts B', which shafts are provided under the frame A with gear-wheels D D, which mesh with each other and cause the rollers to rotate in unison. The lower frame, A', is provided with inclined blocks *d*, which fit within similarly-shaped recesses in the rollers B, and prevent said rollers resting upon the bottom of the frame A', so as to leave a space under which the juices will flow. One of the shafts extends upwardly above the frame A, and to this shaft power is applied for operating the press. To the rear portion of the frames, to the vertical standards *b b*, is secured a box, E, in a slightly inclined position, as shown in Fig. 3, which box is divided longitudinally by a vertical partition, *e*, to the inner end of which is hinged a door, *e'*, the uses of which will be hereinafter set forth. Within the box E are secured two reciprocating plungers, F F, which terminate beneath a feed-spout, G, which spout has a sliding door or gate, *g*. The plungers F F are connected by rods *f f* to a double crank-shaft, H, one end of this crank-shaft being supported in a bracket, *h*, while to the other end is secured a gear-wheel, *h'*, the end of the shaft resting within the bracket *h''*. The gear-wheel *h'* meshes with a gear-wheel, I, attached to the vertical shaft B'.

My invention operates as follows: The apples are first placed in the trough or spout G, and are fed to the rollers B B by the reciprocating plungers, the hinged gate *e'* between said plungers turning so as to prevent the apples entering the space previously occupied by one of the plungers, this gate swinging alternately to the right and to the left. The apples are drawn between the rollers and the juice extracted therefrom, which juice passes out of the spout *a'*, while the pomace passes through the trough C'. The plates C serve to keep the rollers B clean.

I claim—

1. In a cider-press, the combination, with a suitable supporting-frame, of rollers B B,

reciprocating plungers F F, and a hinged gate, e', substantially as shown, and for the purpose set forth.

2. In a cider-press, the frame A', having an upwardly-projecting rim, a, and upwardly-inclined projecting portions d, adjacent to the shafts which carry the pressing-rollers, substantially as shown, and for the purpose set forth.

10 3. In combination with the frames A A', the rollers B B, journaled between the same, feed-trough G, plungers F, crank-connections

with the driving devices, plates C C, bearing against the rollers, as described, and discharge-trough connected to said plates, so as to lead the pomace directly from said rollers, substantially as set forth. 15

In testimony whereof I affix my signature in presence of two witnesses.

STEPHEN BALLARD.
